UNITED STATES PATENT OFFICE.

ELI H. ELDRIDGE AND JOHN H. ELDRIDGE, OF TAUNTON, MASSACHUSETTS.

DESIGN FOR A COFFIN-PLATE.

SPECIFICATION forming part of Design No. 14,641, dated February 12, 1881.

Application filed August 10, 1883. Term of patent 7 years.

To all whom it may concern:

Be it known that we, ELI H. ELDRIDGE and JOHN H. ELDRIDGE, of Taunton, in the county of Bristol and State of Massachusetts, have invented and produced a new Design for Coffin-Plates; and we do hereby declare the following to be a full, clear, and exact description of the same, reference being had to the accompanying drawing, forming part of this specification, and to the figures and letters of reference marked thereon.

Our invention relates to a design for the plates which are placed upon the front or other suitable portions of coffins to bear the name of the deceased and accompanying inscription. Such coffin-plates have heretofore been made in various shapes, with inscription-surfaces surrounded by plain or ornamental borders, and sometimes without borders.

The object of our design is to give the coffin-plates an ornamental, and at the same time a significant, character independent of the special inscriptions.

Our design is shown in the accompanying drawing, and is described as follows: The plate A is formed with a flat face or plain field, B,

bounded on its bottom and sides by substantially straight outlines *a*, and at its top by a curved undulating border, *b*, the latter also constituting the line of separation between the said face B and an upper field, C. Within the field C are arranged emblematical emblems representing a rule, mallet, and trowel, crossed, *f*; a column and globe, *g*; plumb-rules, crossed, *h*; an open bible, with square and compasses thereon, and a letter "G" below, *i*; a sword-point, *j*; another column and globe, *k*, and a winged hour-glass and scythe, *l*, all arranged as shown. The upper part of the plate is bounded by a beveled ornamental scroll-shaped border, *e*.

What we claim is—

The design for a coffin-plate, consisting of the fields B and C and their borders, and the emblematical figures *f g h i j k l* within the field C, the whole arranged as herein described and shown.

ELI H. ELDRIDGE.
JOHN H. ELDRIDGE.
